PROTECTIVE PAD FOR BEDRIDDEN PATIENTS

John F. Gaylord, Jr., Matthews, N.C., assignor to
Medical Specialties, Inc., Charlotte, N.C.

Filed Dec. 18, 1974, Ser. No. 533,798

Term of patent 14 years

Int. CL. D24—04

U.S. CL. D83—1 J

FIG. 1 is a perspective view of a protective pad for bedridden patients, showing my new design;

FIG. 2 is a perspective view as seen from the side opposite of FIG. 1;

FIG. 3 is also a perspective view thereof in a slightly reduced scale and viewed from the side opposite that shown in FIG. 1, and further illustrating the invention as worn on the elbow of a patient;

FIG. 4 is also a perspective view thereof in a scale generally corresponding to that of FIG. 3 and illustrating the invention as worn on the heel of a patient;

FIG. 5 is a top plan view thereof; and

FIG. 6 is a vertical sectional view taken substantially along the line 6—6 of FIG. 1 and in a slightly reduced scale.

The broken lines are shown for illustrative purposes only.

I claim:

The ornamental design for a protective pad for bedridden patients, substantially as shown and described.
